UNITED STATES PATENT OFFICE.

CLARENCE L. TAYLOR, OF ALLIANCE, OHIO, ASSIGNOR TO THE MORGAN ENGINEERING COMPANY, OF ALLIANCE, OHIO.

VALVE MECHANISM FOR STEAM-INTENSIFIERS.

1,302,881.

Specification of Letters Patent. Patented May 6, 1919.

Application filed July 25, 1918. Serial No. 246,706.

To all whom it may concern:

Be it known that I, CLARENCE L. TAYLOR, a citizen of the United States, and a resident of Alliance, in the county of Stark and State of Ohio, have invented certain new and useful Improvements in Valve Mechanism for Steam-Intensifiers; and I do hereby declare the following to be a full, clear, and exact description of the invention, such as will enable others skilled in the art to which it appertains to make and use the same.

This invention relates to an improvement in steam intensifiers for hydraulic presses, shears and similar apparatus, and is designed as an improvement on the construction disclosed in U. S. Patent No. 1,061,839 granted to Hugo Haiss, May 13th, 1913.

The object of this invention is to simplify the valve operating mechanism, so as to lessen the power required to operate them and also to cause the valves to respond quickly and positively to the movements of the actuating levers. A further object is to provide means for preventing the accumulation of air in the hydraulic intensifier cylinder and the high pressure pipe connection between the latter and the press cylinder.

With these and other objects in view, the invention consists in the parts and combination of parts as will be more fully explained and pointed out in the claims.

In the accompanying drawings, Figure 1 is a view in side elevation of the steam intensifier and valve operating mechanism; Fig. 2 is a view in section of the intensifier, the valve operating devices being in elevation; Fig. 3 is a view in plan, the intensifier being shown in dotted lines and the valve actuating devices in solid lines; Fig. 4 is an enlarged view of the valve mechanism; Fig. 5 is a view in section through the valves; Fig. 6 is a view in plan of the latter; Fig. 7 is a view of the rack and gearing for shifting the valves; Fig. 8 is a diagrammatic view showing the cylinder of a press ram connected to the intensifier and the pre-filling valve; Fig. 9 is a view of one of the valve lifting levers and Fig. 10 is a plan view of the double crank in which the valve lifting levers are mounted.

11 represents a steam cylinder, 12 a sin-

gle acting piston and 13 the piston rod which passes through the upper end of the steam cylinder and terminates within the 55 hydraulic intensifier cylinder 14, a suitable packing being provided to prevent leakage. This cylinder 14 is connected at its upper end by pipe 15 with the hydraulic cylinder 16 of a press or other similar apparatus, part 60 of which is shown diagrammatically in Fig. 8, so that the water under compression in cylinder 14 and pipe 15 will be forced directly into cylinder 16.

Secured to the piston 12 is the smooth rod 65 17, which passes through a stuffing box 18 in the head of cylinder 11, and is connected at its upper end by the arm 19 with the upper end of rack bar 20 mounted in the gear casing 21 secured on the projecting flange 70 22 of the cylinder head 23. Rack bar 20 passes through openings in the top and bottom of the casing 21 and is covered and protected below by the tubular sleeve or casing 23^a secured to and depending from the 75 casing 21. The teeth of rack bar 20 mesh with the teeth of pinion 24, the shaft or hub of which is provided with a smaller pinion 25 which in turn meshes with the larger pinion 26 carrying a smaller pinion 27 which is 80 in mesh with the rack bar 28. The shafts of the several pinions are mounted in the gear case 21, and the rack bar 28 passes through the top and bottom members of said casing and is held in position and guided in its 85 movements by the latter. By this arrangement of gear the movement transmitted from rack bar 20, to rack bar 28 is greatly reduced.

Rack bar 28 may be weighted, if desired, 90 and is connected pivotally at its lower end to floating lever 29 midway the ends of the latter, as shown in Figs 1 and 3. This lever 29 is pivotally connected at one end to the upper end of pitman 30, and at its opposite 95 end to the outer end of the crank arm 31, the other end of the said crank arm being rigidly secured to the shaft 32 journaled in bracket 34 secured to the valve casing 35 midway between the stems of the steam 100 supply and exhaust valves. Rigidly secured to the outer end of shaft 32 is the double crank 36 carrying the valve lifting arms 37-38^a, the latter being loosely mounted on

the crank pins so that their adjacent ends are simply lifted and lowered by the rocking movement of the double crank 36. Each valve lifting arm 37 and 37^a is provided 5 adjacent its hub with a toe 38, adapted when the crank 36 is turned in one direction, to engage the lug 39 on the hub of the double crank 36 and hold the arm rigid during the continuation of such turning movement, 10 hence it will be seen that when the crank 36 is turning in one direction, the inner end of arm 37 will be lifted and the inner end of arm 37^a will descend. During the upward movement of the crank pin carrying 15 arm 37, the toe on the latter will engage the lug 39 on the hub of crank 36 (see Fig. 5) and thus lock the arm 37 to the crank during any further upward movement of the latter. While the inner end of arm 37 is 20 moving upwardly, the inner end of arm 37^a is descending and its toe 38 moving away from the lug 39, and when the direction of rocking movement of the crank 36 is reversed the inner end of arm 37^a moves up 25 and the inner end of arm 37 will descend, and operate the steam supply and exhaust valves as will be hereinafter explained.

The outer ends of the arms 37 and 37^a are provided with concave seats 40 which 30 loosely rest on the convex heads 41 of the studs 42 secured to the tops of the valve casings 35, and each arm is provided intermediate its ends, but nearer its outer end, with a concave seat 43 for the convex bearings 44 carried by the valve stems 45, so as 35 to provide for limited sliding movements between the seats and the bearings.

Each valve stem carries a valve both of 40 which are of the puppet type and balanced, the valve 46 being the supply valve for admitting steam from the supply port 48 to the steam cylinder 11, through port 49, and the valve 47 for controlling the exhaust from port 49 to port 50.

45 Pitman 30, which as before explained is connected at its upper end to one end of the lever 29, is connected at its lower end to the crank 51 on the actuating shaft 52, the hub of crank 51 being provided with an arm 53 adapted to engage the adjustable stops 54 for limiting the movement of the crank 51 in its two movements.

50 The valve actuating shaft 52 is provided at its outer end with the handle 55 by which it, and consequently the steam supply and exhaust valves are moved to open positions.

55 In the operation of the apparatus, if the handle 55 be moved to the right, it elevates the pitman 30 and the adjacent end of floating lever 29. In this initial movement of the parts, the floating lever fulcrums on the lower end of rack bar 28, and consequently depresses the outer or rear end of the crank 31. This movement of the crank 31 turns

crank shaft 32 to the right, thus elevating 65 valve actuating arm 37, and lowering the arm 37^a. This movement of the arm 37 lifts valve stem 45 and its valve 46 which permits steam to enter cylinder 11 below piston 12. As the steam enters the cylinder 11, the piston 12 rises, thus elevating the rod 17, and the rack bar 20 connected with said rod, operates through the reducing gear 24—25—26 and 27 to elevate the rack bar 28 at a slower speed. 70 75

After the forward end of floating lever 29 has been elevated to open the steam supply valve 46, the fulcrum of the floating lever is transferred from the lower end of rack bar 28 to the upper end of pitman 30, so that 80 during the remainder of the upward movement of the rack bar due to a continuation of the upward movement of the steam piston, the floating lever turns on its pivotal connection at the upper end of the pitman 30 until it is back to its normal position and both valves closed. During this movement of the floating lever, the latter through the crank 31, double crank 36 and arm 37, lowers the steam valve and cuts off 85 the supply. To exhaust the steam from cylinder 11, handle 55 is moved rearwardly or toward the valve, thus depressing the front end of the floating lever and lifting its rear end, which through the crank 31, shaft 95 32 and lever actuating arm 37^a, lifts valve 47 and permits the steam in cylinder to escape. As the piston descends, rack bar 28 also descends thus gradually lowering the 90 exhaust valve, so that by the time the piston 100 is at the lower end of the cylinder, the exhaust valve will have been closed.

From the foregoing it will be seen that the movement of the floating lever to automatically shift the valves, starts with 105 the upward movement of the steam piston, and the extent of movement of the steam piston is dependent on the throw or movement of the handle 55. If therefore the handle be moved forwardly its full throw, the steam supply valve will be lifted its 110 maximum distance and by the time the piston reaches the limit of its upward stroke the steam will have been cut off. If the handle be moved to an intermediate point, or a shorter distance the throw of the piston will be correspondingly decreased.

115 The pre-filler valve 9 is located at the highest point in the high pressure system between the hydraulic cylinder 14 and the press cylinder 16. The cylinder 14, pipe 15 and the press cylinder 16 are filled with water, so that when the combined piston rod and ram 13 is forced upwardly by the steam piston, the water displaced in the 120 cylinder 14 by the entrance of the ram 13 is forced into the press cylinder and depresses the ram in the well known manner. 125

The press ram 16^a is elevated by the pull back cylinder 56 and their pistons 57 shown in the diagrammatic view Fig. 8.

The pre-filler valve 9, located between the

- 5 water supply tank (not shown) and the high pressure system, opens downwardly and when steam is permitted to escape from beneath the pull back pistons 57, the tendency to a vacuum created in the high pressure system, due to the dropping of the ram 16^a, together with the pressure on the top of valve 9 from the water in the supply tank with which pipe 15^a is connected, causes the valve 9 to open, thus permitting water to
- 10 enter the high pressure system and fill up the space caused by the dropping of the ram 16^a. Some air enters the high pressure pipes with the water and is objectionable as it makes an elastic cushion and causes a hammering or knocking similar to water hammer in water pipe systems. To overcome this I locate the valve 9 at the highest point, so that when the valve 9 is opened, the air escapes thus preventing any accumulation of
- 15 air in the high pressure system. The valve 9 is opened to release the water in high pressure system, when it is necessary to raise the ram by the pull back pistons, by the lever 58, directly or indirectly engaging the outer
- 20 end of valve stem 9^a. This lever is connected by the jointed rod 59—59^a with crank 60 on shaft 61, the latter being provided with a handle 62 by which it is operated.

Having fully described my invention what I claim as new and desire to secure by Letters-Patent, is:—

- 1. The combination of a steam hydraulic intensifier, supply and exhaust steam valves for the intensifier, a floating lever, a rocking shaft carrying means for opening both of said valves, the said rocking shaft being connected with one end of the floating lever, hand operated means connected with the other end of said lever, means connecting the steam piston and floating lever intermediate the ends of the latter whereby the floating lever will be moved by the said piston and speed reducing means forming a part of said connecting means whereby the speed and extent of movement of the floating lever as compared with the speed and extent of movement of the steam piston is reduced.
- 40 2. The combination of a steam hydraulic intensifier, supply and exhaust steam valves for the intensifier, a floating lever, a rocking shaft carrying a double crank, valve lifting arms carried by said double crank, means connecting one end of said floating lever with the rocking shaft for rocking the latter, hand operated means connected with the other end of said floating lever, means connecting the steam piston and floating lever intermediate the ends of the latter

whereby the position of the floating lever 65 is changed by the movements of the piston and speed reducing means forming a part of said connecting means.

3. The combination of a steam hydraulic intensifier, supply and exhaust steam valves 70 for the same, a floating lever, a rock shaft, means connecting said shaft and one end of the floating lever whereby the movements of the lever are imparted to the shaft, two valve lifting arms carried by said rock 75 shaft and actuated by the latter, the said arms having connection with the valve stems, means connecting the steam piston and floating lever whereby the latter has a movement with and in the direction of 80 the piston, speed reducing means forming a part of said connecting means, and hand operated means also connected with said floating lever.

4. The combination of a steam hydraulic 85 intensifier, supply and exhaust steam valves for the same, a floating lever, a rock shaft having crank connection with one end of said lever, hand operated means having connection with the other end of said lever, two 90 valve lifting arms actuated by said rock shaft, whereby their inner ends are alternately elevated and lowered by the rocking movement of the shaft, means loosely supporting the outer ends of the arms when the valves are closed and means connecting the steam piston and floating lever intermediate 95 the ends of the latter for changing the position of the floating lever.

5. The combination of a steam hydraulic 100 intensifier, supply and exhaust steam valves for the same, a floating lever, a rock shaft having crank connection with said lever, hand operated means also connected with said lever, valve lifting arms having indirect pivotal connections with said shaft whereby their adjacent ends will be lifted by the rocking movement of the shaft, means loosely supporting the outer ends of said arms, means connecting the piston and floating lever and speed reducing means forming a part of said connecting means.

6. The combination of a steam hydraulic 105 intensifier, supply and exhaust steam valves, valve actuating mechanism and means including speed reducing gears connecting the piston of the steam cylinder with the valve actuating means, whereby the latter are actuated by the movements of the steam piston.

7. The combination of a steam intensifier, supply and exhaust steam valves, valve actuating means, and means including rack bars and speed reducing gears connecting the rack bars for transmitting movement 115 from the steam piston to the valve actuating means.

8. The combination of a steam intensifier,

supply and exhaust steam valves, valve actuating means, a rack bar having connection with the piston of the steam cylinder, a rack bar connected with the valve actuating means and reducing gears connecting the rack bars.

In testimony whereof, I have signed this
